UNITED STATES PATENT OFFICE

2,040,378

ELECTRICAL GAS TREATMENT

Carl W. J. Hedberg and Robert B. Hesson, Bound Brook, N. J., assignors to Research Corporation, New York, N. Y., a corporation of New York

Application May 8, 1934, Serial No. 724,557

11 Claims. (Cl. 183—7)

This invention relates to the art of electrically treating gaseous fluids and has to do with apparatus comprising complementary electrodes that are to be maintained at a difference of potential therebetween for the purpose of subjecting fluids passing through the apparatus to electrical stresses and/or discharges. For example, the invention can be embodied in an electrical precipitator for removing suspended particles from a stream of gas flowing therethrough.

A principal object of the invention is to provide for the mounting of collecting and complementary discharge electrodes within a treating chamber in such manner that a maximum of the space therein is utilized in treating fluids while they are being passed through the chamber.

Another object is to provide fluid treating apparatus of such construction that distribution of the fluid can be definitely controlled by means within the apparatus itself, thus affording efficient and uniform treatment.

Still another object of the invention is to provide for the division of the electrodes into groups that can be economically supported in insulated relationship and separately energized and otherwise manipulated as required.

Other objects will be apparent from the following description and appended drawings, in which:

0 Fig. 1 is a side elevation partly in section taken along 1—1 of Fig. 2 of the electrical precipitator embodying the invention;

Fig. 2 is a plan view partly in section taken along 2—2 of Fig. 1 of the same precipitator; and

5 Figs. 3 and 4 are fragmentary views showing a detail of the precipitator illustrated in Figs. 1 and 2.

In Figs. 1 and 2, numeral 1 identifies the shell of a precipitator having a gas inlet 2 and gas outlet 3. The precipitator is made up of two similar sections A and B, through which the gas passes in series. Each section comprises two separately spaced and separately supported sets of collecting electrodes 4, 4' and complementary discharge electrodes 5, 5', respectively. All the discharge electrodes in a section are supported from a common supporting frame 6 which in turn depends from a horizontal beam 8 by members 7, in this instance rods, say of steel. Rods 7 extend through holes 9 in the roof of the precipitator, through insulating bushings 10 which cover the holes and prevent gas from escaping through these openings and are fastened to the ends of beam 8. Beam 8, made up of structural steel members or the like, lies across the top of

post insulators 11 which support the beam and insulate it from the grounded portions of the precipitator. Compartment 12 covers the insulators and protects them from atmospheric conditions.

Frame 6 is made up of a saddle-like member 13 to which are fastened vertical members 14 and to the latter are fastened horizontal members 15. The discharge electrode frame proper, marked 60, comprises a vertical strap or bar 16 from which project two horizontal members 17. The 10 discharge electrodes 18 are wires, or they can be small twisted rods. They pass through members 17 and are held by these members in the vertical position shown. Two small electrode frames 60 are shown, one above the other, removably fastened to and supported by main frame 6; but a greater number may be supported in this way or only one may be used depending upon the height of the precipitator, the stiffness of rods 18, and other factors.

Each collecting electrode 4 is made up of a relatively flat member 20 with one vertical edge strongly reinforced as indicated at 21. A hook member 22 is welded or otherwise fastened to edge 21 and with this hook the electrode is supported from horizontal member 23 in non-rigid manner, a hole in member 23 being provided for hook 22. Diagonally across the electrode from this hook is a member 24 that is welded to the electrode and non-rigidly bolted to cam riding member 25. Member 25 rides on the face of cam 26 as does a similar member 25' which is attached to the collecting electrode 4' directly opposite. Cam 26, with similar cams for each pair of collecting electrodes or for each group of collecting electrodes which may be shaken together, is mounted on shaft 27 which is turned slowly by means not shown. It will be noted that rider 25 is shown on the high portion of cam 26 and that the electrode 4 has been pulled away from anvil member 28 against which it would normally rest. With further rotation of cam 26, rider 25 will drop off of cam 26 and the electrode will strike against anvil 28. This operation shakes the collecting electrode and removes the material that has been deposited upon it. Electrodes 4 are loosely held so that the vibration set up by the rapping operation is not greatly damped. Means to guide the electrodes are advisable, however, and in 50 Figs. 3 and 4 such means for guiding the free top corners 30 of the electrodes is shown.

In Figs. 3 and 4, pipe (or bar) member 33 is held against structural member 32 by tap bolts 34 and threaded pins 35 are screwed into member 55

33 in pairs as shown, each pair serving to guide a collecting member 4' (or 4).

Cover members 36 are provided with openings 37 large enough to permit a collecting electrode 5 or a discharge frame 60 to be passed through them. They are covered during operation of the apparatus with plates 38.

Having described a precipitator embodying the present invention, the advantages of such construction can now be readily indicated. It will be noted that there are no members positioned over the collecting electrodes from which discharge members depend, making it possible to position the roof or cover of the precipitator immediately over the tops of the collecting electrodes. Nor are there any high voltage members positioned in the treater chamber in front or at the back of the collecting electrodes holding discharge elements or frames supporting such elements which must pass between the collecting electrodes in these locations. The reinforcing members 21 can therefore be constructed to suit conditions of gas flow and meet structural demands independent of the limitations imposed by the presence of high potential members. The insulators and housings for the same are on top of the precipitator where they are, in general, out of the way of adjacent structures.

Assuming a precipitator two sections long as shown in the figures, practically the total length of the precipitator from wall 39 to wall 40 can be given over to collecting electrodes with adjacent complementary discharge electrodes, except for the two high potential frames 6, one in section A and one in section B. These frames 6 can be quite narrow, even more so than is indicated in the figures, leaving most of the space for precipitating electric fields.

The collecting electrodes are narrow, that is, short in the direction of the gas flow; consequently they are easy to handle during installation, are readily removed for examination, and can be supported by simple non-rigid means and be effectively shaken for removal of deposited material.

Reinforcing means 21 can be made of any desired width and the spaces between means 21 through which the gas flows will vary in width in indirect proportion to the width of means 21. Advantage is taken of this flexibility in construction in obtaining proper distribution of the gas passing through the several treating zones of the precipitator.

The discharge electrode elements are mounted in such manner that they do not pass edges or through constricted openings, making unnecessary the use of shrouds or insulators to suppress discharges at such locations. They are supported on easily dismountable frames 60 and can be removed in small groups for inspection, straightening or replacement while the apparatus is shut down for short periods. This construction provides for great flexibility and discharge elements of different characteristics can be placed in different precipitators of this construction without the necessity of making changes in the electrode supporting structure. It also makes it possible to quickly make changes in discharge electrodes if it is found, during the operation of the apparatus, that members of different characteristics should be placed in different locations to suit the changing electrical properties of the gas as suspended particles are removed from the gas as it passes through the apparatus.

Gas distribution means can be held by the discharge electrode supporting frame 6 if conditions

indicate the need for such devices. Where the discharge frame is used for supporting distribution means and the like it is usually necessary to provide the two rods 7 shown, at least. But in small precipitators where additional distributing means are not so placed and no appreciable gas volume blows against the discharge frame, a single rod 7 only is required.

Electrically the discharge electrodes in section A are independent from those in section B, and, where it is desirable to do so, they can be separately energized. As shown in Fig. 2, section A is energized by means of conductor 44 passing through inlet bushing 45 to insulated beam 8, while section B is energized through conductor 46 which passes into the insulator box of section A through wall bushing 47.

For many problems advantages are found in providing collecting electrodes made up of parallel rods spaced a short distance apart, as described in U. S. Patent No. 1,444,997. There is no material difference in the advantages of the present invention whether the collecting electrodes are perforated or not, but it has been considered more understandable in the present instance to illustrate the invention with imperforate plates 4, 4'. The rapping means for the collecting electrodes can be variously constructed and operated as is known to those versed in the art. For instance, instead of a single centrally positioned shaft rotating the lifting cams, two parallel shafts may be provided, one placed directly under the outer edges of electrodes 4 and the other placed directly under the outer edges of electrodes 4', the cams on these shafts bearing directly upwards on the electrodes mentioned.

We claim:

1. In apparatus for the electrical treatment of gases, a chamber, a plurality of vertically disposed parallel electrode members horizontally arranged in parallel banks in said chamber, and complementary electrode elements supported in alternating relation with said first named electrode members solely by supporting means positioned in the space between said banks of electrode members.

2. In apparatus for the electrical treatment of gases, a chamber, a plurality of vertically disposed parallel collecting electrode members horizontally arranged in parallel banks in said chamber and discharge electrode elements supported in alternating relation with said collecting electrode members, solely by supporting means positioned in the space between said banks of collecting electrode members.

3. In apparatus for the electrical treatment of gases, a chamber, a plurality of vertically disposed parallel collecting electrode members horizontally arranged in two parallel banks in said chamber and discharge electrode elements supported in alternating relation with said collecting electrode members solely by supporting means positioned in the space between said banks of collecting electrode members.

4. In apparatus for the electrical treatment of gases, a chamber, a plurality of vertically disposed parallel collecting electrode members horizontally arranged in two parallel banks in said chamber so as to define a space between said banks, a frame positioned in said space, and discharge electrode elements supported solely by said frame in alternating relation with said collecting electrode members.

5. In apparatus for the electrical treatment of gases, a chamber, a plurality of vertically dis-

- posed parallel collecting electrode members arranged in two parallel banks in said chamber so as to define a space between said banks, means supporting said collecting electrode members substantially wholly from the edges thereof opposite from said space, a frame positioned in said space, and discharge electrode elements supported by said frame in alternating relation with said collecting electrode members.
6. In apparatus for the electrical treatment of gases, a chamber, a plurality of vertically disposed parallel collecting electrode members horizontally arranged in two parallel banks in said chamber so as to define a space between said banks, a frame supported in said space by members depending from the roof of said chamber, and discharge electrode elements supported solely by said frame in alternating relation with said collecting electrode members.
7. Apparatus for the precipitation of suspended material from gases comprising means defining a chamber with gas inlet and gas outlet, a roof on the chamber forming an upper boundary for the gases being treated, collecting electrodes supported vertically in said chamber parallel to the gas flow and having their upper ends adjacent said roof, said collecting electrodes being in two spaced groups through which the gases pass in series, depending means supporting a frame from an insulated structure above said roof, said frame being positioned between the groups of collecting electrodes, members projecting outwardly from said frame, and discharge electrode elements supported between said collecting electrodes by said members.
8. In an electrical precipitator comprising a
- chamber, electrode members within the chamber and extending to adjacent all the walls of said chamber except within a space extending transversely across said chamber intermediate two opposite sides thereof, and a frame in said space entirely supporting complementary electrodes between the first named electrode members.
9. In an electrical precipitator comprising a chamber, collecting electrodes within the chamber and extending to adjacent all the walls of said chamber except within a space extending transversely across said chamber intermediate two opposite sides thereof, and a frame in said space entirely supporting complementary electrodes between the collecting electrodes.
10. In apparatus for the electrical treatment of gases, a chamber, a plurality of vertically disposed parallel collecting electrode members arranged in two parallel banks in said chamber so as to define a space between said banks, a frame supported in said space by members depending from the roof of said chamber, discharge electrode elements supported by said frame in alternating relation with said collecting electrode members, and rapping means for said collecting electrode members positioned in said space below said frame.
11. In an electrical precipitator, a discharge electrode system comprising a vertical supporting frame, discharge electrode supporting members extending outwardly from opposite sides of said frame and a plurality of discharge elements supported in aligned position by said members.
